Medical Products, Inc., Fair Lawn, N.J.

Filed Sept. 29, 1969, Ser. No. 19,329

Term of patent 14 years

Int. Cl. D6—01

U.S. Cl. D15—3

FIG. 1

FIG. 2

FIG. 1 is a front perspective view of a combined chair and attachment tray for use in surgical treatment showing my design wherein the tray is in position for use when treating a hand wound; and

FIG. 2 is a front perspective view of the chair showing the attachment tray in an alternate position for use when treating a foot wound.

The side of the chair not shown is a mirror image of the side shown while the back is conventional in appearance.

I claim:

The ornamental design for a combined chair and attachment tray for use in surgical treatment, as shown and described.
